UNITED STATES PATENT OFFICE.

CHARLES B. YODER, OF WEBSTER GROVES, MISSOURI, ASSIGNOR OF SIXTY ONE HUNDREDTHS TO ISIDOR A. SCHULHERR, OF ST. LOUIS, MISSOURI.

BELT-TIGHTENER.

1,286,482.

Specification of Letters Patent.

Patented Dec. 3, 1918.

Application filed August 25, 1917. Serial No. 188,080.

To all whom it may concern:

Be it known that I, CHARLES B. YODER, a citizen of the United States, residing in the city of Webster Groves, in the county of Saint Louis and State of Missouri, have invented a new and useful Belt-Tightener, of which the following is a specification.

My invention relates to improvements in belt tighteners, especially designed for use 10 in connection with power sewing machines, wherein a pivotally mounted arm, carrying a sheave arranged to ride the machine belt, is acted upon by a spring, which may be varied as to tension by means readily accessible to the machine operator from the top of the machine table.

The object of my improvements is to construct a spring actuated, belt tightener of simple and inexpensive design which may be 20 readily adapted to either straight or twist belts, in which latter case it serves as a separator to prevent wear on the belt, and to arrange means, conveniently accessible to the machine operator and actuatable with a 25 minimum of effort, for varying the spring tension in a minimum of time, to compensate for varying belt conditions.

My improvements consist in the novel construction, arrangement and combination of 30 parts, hereinafter fully, clearly and concisely set forth in my specification, pointed out in my claims and illustrated by the accompanying drawing, in which—

Figure 1 is an elevation, partly in section, 35 of a belt tightener embodying my improvements, showing in section a fragment of a machine top and fragments of a machine pulley and belt.

Fig. 2 is an end elevation of the bearing 40 for the tightener arm and the spring barrel, and

Fig. 3 is a plan of the complete device, removed from the machine.

Referring to the drawings by numerals, 45 designates a base-plate, having counter-sunk screw holes 5, whereby it may be secured to the bottom face of the machine table top. Formed integral with the base-plate, dependently, are the relatively spaced, per- 50 forated ears 7 for the support of a short shaft 8, and in one of said ears there is formed a hole 9 for a pin 10 in order to hold the short shaft against axial movements.

Projecting laterally and integrally from 55 the base-plate, preferably in the plane

thereof, is a web 11 and supported by the web and integral therewith is a cylindrical barrel 12, whose trend is at a right angle to the base-plate 4 and which is internally threaded throughout its length to form a 60 seat for an abutment plug 13, provided with an upstanding and non-circular head 14 to facilitate its adjustment.

Mounted on the short shaft 8 is a rocker arm 15, bifurcated at its free end to receive 65 a sheave 16, which is rotatably mounted on a shaft 17, and arranged to bear on the belt 18, which drives the machine, through the pulley 19, from a power-driven wheel, not shown.

The rocker arm 15, adjacent its pivoted end, carries an abutment cup 20 in opposition to the plug 13 and between which there is arranged an extensible coil spring 21.

In equipping a machine with my belt 75 tightener, a hole, such as 22, is formed through the machine top, vertically and in line with the machine pulley and the power wheel; the barrel 12 extended upwardly therethrough, and, when the machine is a 80 "straight belt drive" the base plate 4 is positioned at a right angle to the trend of the belt and secured by screws, or otherwise, to the bottom face of the machine top, thereby holding the sheave 16 in line with the 85 straight belt.

The arm 15, with the sheave 16, is then 90 pivotally mounted in the ears 7, by means of the short shaft 8 and the spring 21 dropped through the barrel to rest on the 95 cup 20; the abutment plug 13 is then screwed into the barrel a distance to produce the desired spring tension.

When the machine is a "twist belt drive," 95 substantially the same procedure is followed, except for the positioning of the base plate, which is angular to the table top, so that the arm 15 and sheave will parallel the trend of the twist belt, and in which instance the sheave serves to hold the belt at its "point of 100 crossing" from wearing upon itself.

In use the desired "tension" is maintained by a simple rotation of the abutment plug, which may be accomplished, when necessary, by the machine operator and by the employment of a simple socket wrench.

Having thus described my invention, what I claim, as new therein and desire to secure by Letters-Patent of the United States, therefor, is—

1. A belt tightener comprising a sheave, a rocker arm, a pivotal support for the rocker arm, a threaded barrel carried by said support, a spring arranged to act on 5 said rocker arm and means having a threaded connection with said barrel for varying the tension of the spring.
  2. In a belt tightener, the combination with a base plate having means for attachment to a machine top, an integral bearing and an integral, internally threaded barrel, a rocker arm, carrying a sheave, mounted on 10 said bearing and having a spring abutment adjacent said bearing, a spring and a screw- 15 plug abutment in said barrel.
  3. In combination with a machine top having a hole formed vertically therethrough, an open-ended, internally threaded barrel extended through said hole, a pivot support 20 having fixed relation with said barrel and arranged to be secured in various angular relationships with the top, a rocker arm carried by said support, a sheave on said arm arranged to ride the belt of the machine, a
- spring acting on said rocker arm, and a 25 screw plug in said barrel forming an adjustable abutment for the spring.
4. In a belt tightener, an element arranged to bear on a machine belt, a yielding pressure device acting on said element, means 30 for varying the tension of said pressure device and means for securing the belt tightener, as a whole, in various positions to a machine, all of said parts bearing a constant assembled relationship. 35
  5. In combination with a machine top having a hole therethrough, a support arranged to be secured beneath the machine top, an element arranged to be connected with said support and to ride a driving belt for the 40 machine, and a tension device arranged to bear on said element and having an adjustable part located with relation to said hole as to be susceptible of adjustment, to effect a variation of tension on the belt, through 45 said hole and from the upper side of the machine top.

CHARLES B. YODER.
